UNITED STATES PATENT OFFICE.

MARTIN J. DONER, OF CHICAGO, ILLINOIS, ASSIGNOR OF ONE-THIRD TO CHARLES G. GIBSON AND ONE-THIRD TO CHARLES F. DYNES, BOTH OF CHICAGO, ILLINOIS.

CORNER-BEAD.

1,015,881.

Specification of Letters Patent. Patented Jan. 23, 1912.

Application filed October 9, 1911. Serial No. 653,507.

To all whom it may concern:

Be it known that I, MARTIN J. DONER, a citizen of the United States, residing in the city of Chicago, county of Cook, and State of Illinois, have invented certain new and useful Improvements in Corner-Beads, of which the following is a specification.

This invention relates to improvements in corner beads and refers more particularly to 10 a metal corner bead for holding or supporting the plaster at the corners or angles of the walls of a building, and the like.

Among the salient objects of the invention are to provide a construction which obtains a maximum efficiency in maintaining plastering or lathing in place at the corners of the walls and which at the same time will effectively resist a sudden blow or shock of considerable violence; to provide a construction in which the wings of the corner beads are so arranged that excessive pressure tends to further close or tighten the head of the bead instead of spreading it apart at its joint as in the prior art devices; to provide a 20 construction which dispenses with the necessity of any strengthening plate or rod; to provide a construction which may be readily applied to any thickness of plaster or bent to fit any desired curve in the corner of a 25 wall; to provide a construction which is particularly characterized by its cheapness in manufacture and which is nevertheless reliable and simple in construction; and in general to provide an improved device of 30 the character referred to.

Referring to the drawings—Figure 1 is a side elevation of my improved corner bead shown as applied to a wall, with parts of the plaster broken away in order to show 40 the construction of the bead. Fig. 2 is a horizontal sectional view of the construction shown in Fig. 1. Fig. 3 is a fragmentary perspective view of the corner bead. Fig. 4 is a horizontal sectional view of the construction shown in Fig. 3. Fig. 5 is a plan view of a sheet of metal showing the manner 45 of cutting out corner beads.

My invention consists in the matters hereinafter described and more particularly 50 pointed out in the appended claims.

In the drawings, 1 designates as a whole my improved corner bead, which is formed from a single piece of sheet metal bent along 55 its central or medium lines to form a tubular head 2, having a tubular outer face 3 and

sides 4 and 5. The sides 4 and 5 of the head are bent to form the joint 6. At the joint 6, each side of the head is provided with a plurality of spaced apart and alternately disposed wings 7, each of the wings terminating in a tongue or eye.

The corner bead is applied to the wall in the usual manner, nails being driven through the edges 8 into the lathing or wall, the plastering is then applied in the well known 65 manner.

The corner beads may be of any desired length. The blanks from which these beads are formed are preferably struck out in the manner shown in Fig. 5, i. e., a blank is 70 struck out as shown in full lines in Fig. 5 and the succeeding blank is struck out along the dotted lines as shown in Fig. 5, this manner of striking out the blank obviously reduces the cost of manufacture, as there is a 75 minimum of waste. It is to be noted that the head of the bead may be so struck as to present a neat and finished appearance while at the same time is extremely strong. Pressure on the head of the bead it is true 80 has a tendency to spread the wings 7 apart but instead of this weakening or opening the bead along the joint it further closes the joint.

Difficulty has been experienced in many of the prior art devices in preventing the head of the bead from spreading under excessive shock. Applicant's device is so constructed that excessive pressure rather strengthens 85 than weakens the bead in so much as it closes instead of opens the joint. It will be further noted that the wings while formed from a minimum amount of metal are nevertheless sufficiently strong for practical purposes.

I am aware that devices of this character have been patented numerous times but none of them combine the strength and efficiency of my device with extreme economy in manufacture, and it may be stated here that economy in manufacture is one of the prime 95 requisites in a device of this character.

The particular shape of the wings or eyes may be more or less varied in an obvious manner.

I do not limit myself to the details of construction shown except as set forth in the appended claims.

I claim as my invention:

1. A corner bead formed from a single piece of sheet metal bent centrally to form a 110

closed hollow head, said head consisting of a tubular outer face and two sides meeting to form a joint, a plurality of spaced apart skeleton wings extending from one side of the head and over-lapping the joint, and a plurality of spaced apart similar wings extending from the other side of the head and likewise over-lapping the joint, the wings of one side being alternately disposed with the wings of the other side of the head, each of said wings terminating in an eye or tongue portion for attachment to the wall, said wings being so arranged that pressure on the head tends to close instead of open the joint.

2. A corner bead formed from a single piece of metal bent centrally to form a closed

hollow head, the joint thereof being along the inner edge of the head, a plurality of spaced apart wings extending from one side of the head and overlapping the joint, a second series of similarly arranged wings alternately disposed with reference to the members of the first series and extending from the other side of the head and over-lapping the joint, said sets of wings being angularly disposed relative to each other whereby the pressure on the outer side of the head tends to close the head at its joint.

MARTIN J. DONER.
